UNITED STATES PATENT OFFICE.

LUDWIK MICEUSZ, OF HOLDEN, WEST VIRGINIA.

WRENCH.

Specification of Letters Patent.

Patented Dec. 31, 1912.

1,048,994.

Application filed October 11, 1912. Serial No. 725,198.

To all whom it may concern:

Be it known that I, LUDWIK MICEUSZ, a subject of the Emperor of Austria-Hungary, residing at Holden, in the county of Logan 5 and State of West Virginia, have invented certain new and useful Improvements in Wrenches, of which the following is a specification.

This invention relates to wrenches, and 10 the objects of my invention are to provide a wrench of that type commonly styled a "monkey-wrench," with simple and effective means for rapidly moving the adjustable jaw of a wrench, and to provide the wrench 15 with a novel locking mechanism for holding the movable jaw in adjusted position.

Further objects of my invention are to provide a strong and durable wrench of the above type, and to accomplish the above results by a mechanical construction that is 20 inexpensive to manufacture, and efficient as a gripping device for rotating nuts.

With the above and other objects in view the invention resides in the novel construction, combination and arrangement of parts 25 to be hereinafter specifically described and then claimed.

Reference will now be had to the drawing, wherein:

30 Figure 1 is a side elevation of a wrench in accordance with this invention, Fig. 2 is a front elevation of the same, Fig. 3 is a longitudinal sectional view of the wrench, and Fig. 4 is a horizontal sectional view 35 taken on line IV-IV of Fig. 3.

A wrench in accordance with this invention comprises a handle 1 having the inner end thereof provided with a longitudinal recess or bore 2 that is rectangular in cross 40 section. Slidably mounted in the recess or bore 2 is a shank 3 having the outer end thereof provided with a jaw 4 presenting a flat gripping surface 5 at the front side of the shank. The front side of the shank is 45 provided with transverse ratchet teeth 6 and the inner end of the shank is provided with a screw 7 that extends through a longitudinal slot 8 formed in the side of the handle. The outer end of the screw 7 has a flat head 50 or finger piece 9 that rides against the side of the handle 1, and it is through the medium of this finger piece that the shank 3 can be rapidly shifted, in either direction in the handle 1.

55 The front side of the handle 1 is provided

with sets of apertured lugs 10 and 11, also with a jaw 12 that is located at the outer end of the handle, said jaw presenting a flat gripping surface 13 that confronts the gripping surface 5 of the jaw 4 and co-operates 60 therewith in gripping the facets of a nut.

Pivotsly mounted between the apertured lugs 10 by a transverse pin 14 is a lever 15, said lever having the inner end thereof enlarged to provide a hand grip 16. This 65 hand grip has the inner face thereof recessed, at 17 to receive the end of a compression spring 18 that is located in a recess 19 provided therefor in the front side of the handle 1. The outer end of the lever 15 is bifurcated, as at 20 and pivotally mounted in the bifurcation of said lever by a pin 21 is the reduced inner end 22 of a locking arm 23. This arm is pivotally mounted by a transverse pin 24 between the 70 apertured lugs 11 and the outer end of said arm has a tooth 25 to enter an opening 26 provided therefor in the front side of the handle 1 and engage the ratchet teeth 6 of 75 the shank 3.

There is sufficient play between the connected ends of the lever 15 and the arm 23 to permit of said arm being shifted by pressing upon the hand piece 16 of the lever. 80 The arm 23 is held by the lever 15, through 85 the medium of the spring 18, whereby the tooth 25 will remain normally out of the opening 26, consequently the shank 3 can be freely moved within the handle 1, but is limited in its movement by the screw 7 engaging the ends of the slot 8. After the jaws 4 and 12 have been placed in engagement with the facets of a nut, the hand piece 16 of the lever 15 can be gripped with 90 the handle 1 and the tooth 25 shifted 95 through the opening 26 to engage the ratchet teeth 6 and hold the shank while the wrench is being used for rotating the nut.

What I claim is:

A wrench comprising a handle having the outer end thereof provided with a longitudinal bore, a toothed shank slidably mounted in the bore of said handle, a jaw carried by the outer end of said shank, said handle having a longitudinal slot formed therein in communication with the bore of said handle, a screw carried by the inner end of said shank and extending through said slot and having a finger piece to facilitate moving said shank, a lever pivotally 100 105 110

mounted upon the front side of said handle, a compression spring located in the front side of said handle and engaging the inner side of said lever at the inner end thereof, 5 a locking arm pivotally mounted upon the front side of said handle and having the inner end thereof loosely connected to the outer end of said lever, and a tooth carried by the outer end of said locking arm and

adapted to extend through the front side 10 of said handle to engage said toothed shank.

In testimony whereof I affix my signature in presence of two witnesses.

LUDWIK MICEUSZ.

Witnesses:

FOMAZS MICEUSZ,
FRENK SLOWIK.
